A. HENWOOD,
PROCESS OF OXIDIZING AMMONIA TO NITRIC ACID,
APPLICATION FILED JAN. 9, 1919,
1,347,159. Patented July 20, 1920.

UNITED STATES PATENT OFFICE.

ABRAHAM HENWOOD, OF CYNWYD, PENNSYLVANIA.

PROCESS OF OXIDIZING AMMONIA TO NITRIC ACID.

1,347,159.

Specification of Letters Patent.

Patented July 20, 1920.

Original application filed July 8, 1918, Serial No. 243,758. Divided and this application filed January 9, 1919. Serial No. 270,409.

To all whom it may concern:

Be it known that I, ABRAHAM HENWOOD, a citizen of the United States, residing at Cynwyd, county of Montgomery, and State of Pennsylvania, have invented a new and useful Improvement in Processes of Oxidizing Ammonia to Nitric Acid, of which the following is a full, clear, and exact description, reference being had to the accompanying drawing, which forms a part of this specification.

The purpose of my invention is to secure a maximum yield of nitric acid of maximum concentration from the oxidation of ammonia gas.

In an application filed by me July 11, 1917, Serial No. 179,804, for process of the oxidation of ammonia to nitric acid, I have set forth a process wherein ammonia gas and oxygen are passed over a catalyzer while maintaining a partial pressure of oxygen equal to or greater than twice the partial pressure of the ammonia gas and forming the majority, and preferably at least two-thirds, of the total gas pressure, the pressure being sufficient to promote rapid reaction but insufficient to cause excessive heating of the catalytic body or to cause heating to a point detrimental to the formation of nitric acid. The said application also sets forth other features of novelty, some of which are not therein claimed.

While said application, Serial No. 179,804, discloses the subject-matter herein claimed, the present application is more properly a division of an application filed by me July 8, 1918, Serial No. 243,758, wherein not only is the same process described, but the same apparatus is used to carry out the process.

The invention herein set forth comprises a process involving the passage of ammonia gas and oxygen over a catalyzer wherein the proper temperature at the point of reaction is maintained by cooling by one means, preferably by gas control, and specifically by excess of oxygen, to a temperature near the lower part of the permissible range of temperatures, and correcting for excess of reduction of temperature, and thereby securing the ideal temperature desired, by heating by another means, preferably by outside automatically acting thermostatically-controlled electrical means, whereby the temperature of reaction may be at all times

maintained with the range of temperature high enough to secure maximum concentration of nitric acid but not sufficiently high to permit any substantial decomposition of nitric acid.

In my said application Serial No. 179,804, I have explained that the temperature can be regulated entirely by the use of excess oxygen and adjustment of the quantity of excess for selected tube size and quantity of catalyzer, readily determinable by experiment, or by varying the gas speed, reducing the quantity of gas and, as a consequence, reducing its pressure to reduce its temperature. The present invention does not comprehend the regulation of temperature solely by gas control, but contemplates the lowering and raising of the temperature by respectively different agencies, the method of lowering the temperature by gas control, described in said application, being supplemented by an outside, automatic, and preferably thermostatically-controlled and electrical means, to prevent the dropping of the temperature below the minimum range of efficiency.

In said application, Serial No. 179,804, and also more specifically in said application filed July 8, 1918, Serial No. 243,758, of which this application is a division, I have described the passage of the gases through a specific type of catalyzer which is especially adaptable to the oxidation of ammonia to nitric acid. This process forms the subject-matter of the claims of said application Serial No. 243,758, and while it is not herein claimed, still the process of the present application operates with the highest degree of efficiency and economy if this special improved type of catalyzer be employed and I therefore herein generally describe the same in connection with the description of the thermostatically-controlled electrical heating means employed in connection therewith.

The successful employment of this improved catalyzer seems to be dependent upon supporting it in such manner as to avoid impairment or destruction of its efficiency. While this feature of the complete process is specifically set forth and claimed in a separate application Serial No. 270,410, filed January 9, 1919, which is also a division of said application Serial No. 243,758, I have deemed it advisable to here-

in briefly describe such method of support in connection with the description of the thermostatically-controlled means associated therewith for maintaining the temperature at the catalyzer within the range of efficiency and safety.

The catalyzer that I prefer to employ comprises a continuous porous or permeable contact or reaction surface, or diaphragm, of catalytic material, preferably platinum sponge, the mass of catalytic material being so small as not to be self-sustaining but distributed uniformly over the surface of a porous or permeable material which is preferably non-metallic, non-catalytic, and a poor conductor of heat.

A base or support of such material of any suitable shape, so covered with a coating, film or diaphragm of platinum, is placed in the channel provided for the reaction gases so that the latter must pass over or through the same and hence be brought into reactive contact with the continuous surface of platinum. Thus I attain maximum economy, even distribution, minimum mass and uniform temperature, and insure that practically every molecule of the reaction gases will be subjected, and in the same degree, to the influence of the catalyzer.

In preparing the catalyzer, I take a support, which may be in the shape of a disk, hemisphere, tube, or any other shape, made of porous or permeable material, such as alundum or silica. The catalytic material, preferably platinum, is deposited, formed or placed, on either or both surfaces of the support, but preferably only on one surface. The catalytic material may be applied in various ways, but I prefer to soak an alundum support in ammonium chlorid, dry it, remove any excess from the surface, spray upon the surface a platinum chlorid solution, thereby forming on the surface a precipitate of ammonium chlorplatinate, and then dry and ignite, thus burning off or volatilizing ammonia, hydrogen chlorid, steam and chlorin, and leaving a superficial layer of platinum sponge.

To prevent cracking of the support due to expansion and contraction resulting from variation of temperature at the beginning and end of a run, the edge of the support may be sustained in a groove containing a plastic lute, composed of a vitreous substance of the proper degree of viscosity at the working temperature, and which is chemically inert to the reaction gases, thereby providing an hermetical seal which allows the support to expand as it is heated and contract as it is cooled. I prefer to use a sustaining seal or lute composed of boric acid.

To secure a fine and certain adjustment of the temperature, which is the subject of the present invention, I use, as hereinbefore

stated, sufficient excess oxygen, or, less desirably, sufficiently reduce the gas speed, so that the temperature will tend to border on, or even sink below, the lower limit of the range of permissible temperatures, and then add heat from outside, by automatically-controlled, and preferably thermostatically-controlled, means to maintain the temperature safely above the lower limit of the range of permissible temperatures, thereby offsetting what would otherwise be objectionable depressions of temperature below that at which the reaction takes place advantageously. The heating may be effected by a resistance wire winding arranged in an electric circuit and in proximity to the catalyzer and also to a thermostatic element which is connected to, and operates, a rheostat controlling the flow of electric current, so as to cut out resistance as the temperature decreases and introduce resistance as the temperature increases and break the circuit altogether at any desired upper limit of temperature.

The practice of my process does not depend upon the employment of any particular apparatus, and any known apparatus for mixing the gases of reaction and for condensing the nitric acid may be employed. That part of the apparatus including and adjacent the catalyzer may also be constructed and arranged as desired, provided the construction and arrangement are such as to permit the effective execution of the process. The annexed drawing, therefore, must be considered as merely illustrative of one of the different ways available for practising the process.

The figure is a diagram of that part of the apparatus which may be conveniently called the reaction chamber, including the thermostatically-controlled outside heating means.

In the figure, *a* and *b* are two sections of a tube or chamber into which the gases of reaction pass and combine to form nitric acid. The tube, at the junction of the two sections, is bent circumferentially to form a circumferential groove *c* containing boric acid *d* or some equivalent substance that is plastic, vitreous, viscous and chemically inert to the gases. The disk-shaped support *e* composed (say) of silica, holding distributed over its surface, in a continuous manner, platinum sponge *f*, has a depending peripheral flange *g* resting in the groove *c* and embedded in the plastic lute *d*, which, while providing an hermetical seal, allows the disk *e* to expand and contract. The support is either inherently porous or is provided with perforations which permit the free flow therethrough of gas and acid. It is also adapted to be highly heated without injury and to retain the heat from the reaction taking place at this point.

A resistance wire winding *h* incloses the tube containing the catalyzer and is coiled also about the stem of a thermostatic element *i*, whose outer end, insulated at *j*, is connected with the arm *k* of a rheostat *m*, by which the flow of current from a battery *n* is controlled. A switch *o* provides for opening the circuit when automatic operation is not desired or required.

- 10 I do not herein claim the catalyzer, or the combined catalyzer and support therefor, or the means for retaining the support in position and at the same time permitting it to expand or contract, or the process of 15 catalytically combining oxygen and ammonia gas to form nitric acid by passing the mixture through said catalyzer or, while so doing, supporting the catalyzer carrier flexibly to provide for its expansion and 20 contraction. These inventions form the subject-matter of separate applications, namely: Serial No. 243,758, filed July 8, 1918; Serial No. 241,724, filed June 25, 1918; and Serial No. 270,410, filed January 25 9, 1919.

Having now fully described my invention, what I claim and desire to protect by Letters Patent is:

1. The method of keeping down the 30 temperature in the oxidation of ammonia gas into nitric acid which consists in providing for a non-automatic temperature reduction and correcting for excess of reduction by an automatic addition of heat as the lower

range of permissible temperature is approached. 35

2. The method of maintaining the proper temperature at the point of reaction in oxidation of ammonia gas into nitric acid which consists in providing for a normal 40 low temperature for the reaction and automatically heating by outside thermostatically-controlled means when the temperature falls below the designed point.

3. The method of maintaining the proper 45 temperature at the point of reaction in oxidation of ammonia gas into nitric acid which consists in cooling the gases at the point of reaction by gaseous means to a point in the lower part of the range of permissible 50 temperature and protecting from excessively low temperatures by thermostatically-controlled outside means.

4. The method of maintaining the proper 55 temperature at the point of reaction in oxidation of ammonia gas into nitric acid which consists in cooling at the point of reaction by excess of oxygen to a temperature near the lower part of the permissible range of temperatures and adding heat by 60 thermostatically-controlled electrical means when the temperature approaches too closely to the lower limit.

In testimony of which invention I have hereunto set my hand at Cynwyd on this 65 26th day of December, 1918.

ABRAHAM HENWOOD.
